United States Patent Office

Des. 185,280
Patented May 26, 1959

185,280

HIBACHI

Morris Greenblat, Burlingame, Calif.

Application December 12, 1958, Serial No. 53,754

Term of patent 14 years

(Cl. D81—10)

Fig. 1 is a perspective of an hibachi showing my new design;

Fig. 2 is a top plan view thereof;

Fig. 3 is a front elevation thereof; and

Fig. 4 is a side elevation.

I claim:

The ornamental design for an hibachi, as shown.
